UNITED STATES PATENT OFFICE.

HERMAN C. VIZENTS, OF CHICAGO, ILLINOIS, ASSIGNOR, BY MESNE ASSIGNMENTS, TO TOM McNAUGHTON, OF LONDON, ENGLAND.

TIME-STAMP GAGE DEVICE.

No. 909,731.

Specification of Letters Patent.

Patented Jan. 12, 1909.

Application filed June 1, 1908. Serial No. 436,146.

To all whom it may concern:

Be it known that I, HERMAN C. VIZENTS, a citizen of the United States, residing at Chicago, in the county of Cook and State 5 of Illinois, have invented a new and useful Improvement in Time-Stamp Gage Devices, of which the following is a specification.

My invention consists of a novel construction of gage-device for use, more particularly, as an attachment on the bed-plate of a time-stamp to facilitate using the latter by guiding into position a card to be stamped by the employee for noting thereon the time of his coming in or going out, the time of 15 beginning or finishing a piece of work, or the like.

Referring to the accompanying drawings, Figure 1 shows my gage-plate by a view in end elevation in its operative position on a 20 time-stamp, which is illustrated by a dotted representation; Fig. 2 shows the gage-plate by a view in front elevation; Fig. 3 is a plan view of the same, with a time-card, shown dotted, in position thereon; Fig. 4, a similar 25 view of the time-card; Fig. 5, a view in end elevation of the gage-plate, showing the end thereof opposite that presented in Fig. 1; Fig. 6, a section on the irregular line 6, Fig. 5, and Fig. 7, a broken perspective view 30 showing the index-knob of the device in un-assembled relation to the plate.

The plate 8, which is of general rectangular form and shown to be provided with rounded corners, is adapted to seat upon the 35 bed of a time-stamp 9 of any desired construction, to which it is fastened, as by screws. In the part of the plate which is imposed on said bed is contained an opening 10 to register with the impression-pad 40 of the stamp against which its swinging type-head operates. At intervals along the portion of the plate which projects beyond a side of the stamp-bed are provided therein parallel transverse slots 11, 12, 13, 14; and 45 extending in the plane between the slots 11 and 12 is a longer slot 15 parallel with a similar slot 16 extending in the plane between the slots 13 and 14 and adjacent to which are marked on the plate, in succession along the slot the abbreviated names of 50 the seven days of the week. The plate bears the legend "A. M. In." in line with the slot 11, "A. M. Out." in line with the slot 12, "P. M. In." in line with the slot 13, and 55 "P. M. Out." in line with the slot 14, or

such other matter as may be required to correspond with printed matter on a time-card.

In depending bearings 17 and 18 on the plate is journaled a shaft 19 carrying stop-fingers 20, 21, 22 and 23 respectively registering with the slots 11, 12, 13 and 14 to be protruded through them, these fingers extending successively at right-angles to each other. This shaft has slight longitudinal movement in its bearings against the resistance of a spiral spring 24 surrounding it and confined between the hub of the finger 23 and the bearing 18 beyond the outer face of which the shaft 19 projects concentrically 70 with a series of pin-holes 25, 26, 27 and 28, corresponding in number with the stop-finger slots and formed equidistant apart in the outer face of the bearing, to be engaged by a pin 29 projecting from the hub of a 75 handle 30, or knob, secured on the protruding end of the shaft and affording the medium by which to pull it outwardly and turn it. The knob 30 is shown in its preferred square form, and bears on its four 80 edge-surfaces legend-matter corresponding, respectively, with that at the ends of the stop-finger slots. A gage-bar 31 is reciprocably supported on the face of the plate 8 and has depending from it similar bifurcated 85 guide-legs, 32, 32, which project through the slots 15 and 16 and are connected by a thin slide-strip 33 of spring-steel bearing against the under face of the plate for confining the gage-bar thereon and permitting it to be 90 reciprocated freely for registering it with the respective names of the days of the week on the plate. The gage-bar is reciprocated through the medium of a rod 34 having its ends movably confined in the forks of the 95 legs 32, this rod being carried on the ends of similar arms 35, 35, extending correspondingly from a rock-shaft 36 journaled in bearing-lugs 37 and 38 depending from the plate 8 and having slight longitudinal play in its 100 bearings against the resistance of a spiral spring 39 confined between the lug 38 and the hub of the adjacent arm 35.

To operate the shaft 36 it is provided on its outer end with a knurled knob 40, or 105 handle, carrying a finger 41 from which a pin 42 projects laterally to engage with any one of a series of seven holes or depressions 43 provided to describe an arc of a circle in the outer face of the lug 38. A tongue 47 110

extends from the bar 31 along an edge of the slot 11 and affords means for confining a time-card in position on the gage-plate while the card is being stamped as hereinafter 5 described.

A time-card 45, shown in Fig. 4 as suitable for use with my device, has a space 46 on it for the name of the employee to whom it relates, and a space 46¹ for his number, and 10 is ruled with longitudinal lines forming between them seven spaces denoting the days of the week and with transverse lines forming four columns headed respectively, "In", "Out", "In", "Out", and "Total"; though 15 this matter is subject to variation to correspond with matter on the index-knob 30 different from that shown.

To use the gage-device the bar 31 is set to 20 register with the proper name of any day of the week in the line of the names. This may be done at the beginning of each day by pulling outward on the knob 40 to free the pin 42 from a hole 43 and permit turning of the shaft 36 and finger 41 to register the pin 25 with the hole 43 corresponding with the name of the day, with which the gage-bar is required to register, thus with "Monday" as 30 represented in Fig. 3. So turning the shaft moves the arms 35 to engage the rod 34 carried by them with the bifurcated legs 32 and thereby move correspondingly the bar 31 into the desired registry, wherein it is locked, upon release of the knob 40, by the recoil of the spring 39 engaging the pin 42 with the 35 proper hole 43. With the device thus set for the day the employees, as they come in and go out, adjust their respective cards 45 into proper position upon the plate 8, each by inserting a card under the tongue 47 with its 40 top-edge against the bar 31, and works the time stamp in the usual manner.

To cause the card to be stamped with the time of coming in the morning, the knob 30 is pulled outwardly to free its pin 29 and 45 permit it to be turned to display uppermost the "A. M. In." upon it, and thereby turn the shaft 19 to project the stop-finger 20 through the slot 11 into the path of the advance-edge of the inserted card; and on releasing the knob, the spring 24 retracts the shaft to lock it by engagement of the pin 29 with the hole 25. While the finger 20 occupies that position it affords a stop against inserting the card further than is necessary 50 to properly register it for stamping in the first column on its left-hand end headed "In", for the morning of the day, during 55 which, when an employee goes out, he adjusts the shaft 19 to protrude the finger 21 through the slot 12, whereby the knob is caused to display "A. M. Out", and that finger then affords a stop against inserting the card further than required for properly 60 registering it to be stamped in the next succeeding column headed "Out". In the 65

same manner the device is set for stamping "In" and "Out" columns relating to the afternoon on the card by causing the finger 22 or 23, as the case may be, to protrude through the respective slots 13 and 14 and afford a stop for properly limiting the extent of inserting the cards in adjusting them into place to be stamped. 70

What I claim as new and desire to secure by Letters Patent is— 75

1. A gage-device comprising a plate containing an opening and a series of slots, a shaft journaled on said plate and carrying stop-fingers extending from it at different angles to be protruded through the respective 80 slots by turning the shaft, a gage-bar supported on said plate and movable on the face thereof, and means for moving said bar, substantially for the purpose set forth.

2. A gage-device comprising a plate containing an opening and a series of slots and provided with designating characters relating to the slots, a shaft journaled in bearings on said plate and provided with an operating knob, locking means for the shaft, stop-fingers extending at different angles from the shaft to be protruded, by turning it, through the respective slots, a gage-bar supported on said plate and movable on the face thereof, means for moving said bar, and a series of 90 designating characters on the plate with reference to which said bar is movable, substantially for the purpose set forth. 95

3. A gage-device comprising a plate containing an opening and a series of slots, a shaft journaled on said plate and carrying stop-fingers extending from it at different angles to be protruded through the respective slots by turning the shaft, a gage-bar supported on said plate and movable on the 100 face thereof, a tongue extending from said bar, and means on the plate for moving said bar, substantially for the purpose set forth. 105

4. A gage-device comprising a plate containing an opening and a series of slots and provided with designating characters relating to the slots, a shaft journaled and longitudinally movable in bearings on said plate and spring-retracted lengthwise, a knob on said shaft bearing characters relating to 110 those of the slots and provided with a locking pin, a series of pin-holes in the outer shaft-bearing for engaging said pin, and stop-fingers extending at different angles from the shaft to be protruded, by turning it, through the respective slots, substantially for the purpose set forth. 115

5. A gage-device comprising a plate containing an opening and a series of slots and provided with designating characters relating to the slots, a shaft journaled and longitudinally movable in bearings on said plate and spring-retracted lengthwise therein, a knob on said shaft bearing characters relating to those of the slots and provided with 120 125 130

a locking-pin, a series of pin-holes in the outer shaft-bearing for engaging said pin, stop-fingers extending at different angles from the shaft to be protruded, by turning it, through the respective slots, a gage-bar supported on said plate and movable on the face thereof, means for moving said bar, and a series of designating-characters on the plate with reference to which said bar is 10 movable, substantially for the purpose set forth.

6. A gage-device comprising a plate containing an opening and a series of slots, a shaft journaled on said plate and carrying 15 stop-fingers extending at different angles therefrom to be protruded through the respective slots by turning the shaft, a gage-bar having legs protruding through guide-slots in the plate with a slide-strip connecting them on the under side of the plate, a 20 second shaft journaled in bearings on the plate and connected with said legs for moving said bar, and a series of characters on the plate with reference to which said bar is 25 movable, substantially for the purpose set forth.

7. A gage-device comprising a plate containing an opening and a series of slots, a shaft journaled on said plate and carrying 30 stop-fingers extending from it at different angles to be protruded through the respective slots by turning the shaft, a gage-bar having legs projecting through guide-slots

in the plate with a slide-strip connecting them on the under side of the plate, a second 35 shaft journaled in bearings on the plate and connected with said legs for moving said bar, locking-means for said second shaft, and a series of characters on the plate with reference to which said bar is movable, substantially 40 for the purpose set forth.

8. A gage-bar comprising a plate containing an opening and a series of slots, a shaft journaled on said plate and carrying stop-fingers extending at different angles therefrom to be protruded through the respective slots by turning the shaft, a gage-bar having 45 bifurcated legs projecting through guide-slots in the plate, with a slide-strip connecting them on the under side of the plate, a 50 second shaft journaled and longitudinally movable in bearings on the plate and spring-retracted lengthwise therein, with arms extending from it and carrying a rod engaging said legs, a series of pin-holes describing an 55 arc on the outer bearing of said second shaft, a knob on said second shaft carrying a finger provided with a pin for engaging said holes, and a series of characters on the plate with reference to which said bar is movable, substantially 60 for the purpose set forth.
